UNITED STATES PATENT OFFICE.

FRANK B. BRADLEY, OF CHICAGO, ILLINOIS.

DESIGN FOR A CHAIR FOR RAILWAY-SWITCHES.

SPECIFICATION forming part of Design No. 32,642, dated May 8, 1900.

Application filed March 26, 1900. Serial No. 10,295. Term of patent 7 years.

To all whom it may concern:

Be it known that I, FRANK B. BRADLEY, a citizen of the United States, residing at Chicago, in the county of Cook and State of Illinois, have invented a certain new and useful Design for a Chair for Railway-Switches, of which the following is a specification.

This invention relates to a design for a chair for railway-switches, and has for its object to produce a new and useful design of characteristic and distinguishing appearance which presents to the eye a design readily distinguishable from all prior designs for chairs for railway-switches.

15 In the drawings, Figure 1 is a perspective view of a chair embodying my design, and Fig. 2 is a transverse section thereof on the line 2 2 of Fig. 1.

The essential feature of my design consists 20 of the generally-rectangular body portion thereof, having a generally-circular opening therein, the walls of said opening being outlined by a series of truncated teeth or projections.

25 As shown in the drawings, my design consists of the generally-rectangular flat body A, the flat rectangular extension or head B,

which stands at a right angle to the body portion, and the flat rectangular neck portion C, connecting the body and the head, said neck 30 C being in a plane oblique to both the body and the head and being of less width than either the body or the head. In the body A is formed a substantial center opening D, which is generally circular, although the side 35 walls thereof are outlined by an irregular line producing a toothed surface, the teeth E being substantially truncated cones, extending inwardly from the walls of the circular opening. This generally-circular opening, having inwardly-extending radially-disposed teeth around its periphery, gives to the design a characteristic and distinguishing appearance.

Having thus fully described my invention, 45 what I claim, and desire to secure by Letters Patent, is—

The design for a chair for railway-switches, substantially as shown and described.

FRANK B. BRADLEY.
